COMBINATION AIRPLANE AND HELICOPTER

Charles J. Fletcher, Sparta, N. J.

Application November 4, 1954, Serial No. 32,964

Term of patent 14 years

(Cl. D71—1)

Fig. 1

Fig. 2

Fig. 3

Figure 1 is a front view of a combination airplane and helicopter with the wheels in extended position embodying my new design;

Figure 2 is a perspective right rear view thereof;

Figure 3 is a perspective right front view thereof with the wheels retracted;

Figure 4 is a side elevation view thereof with the wheels in extended position;

Figure 5 is a top plan view thereof; and

Figure 6 is a fragmentary enlarged detail view of the rear portion of the fuselage with the cargo doors in open position.

What I claim is:

The ornamental design for a combination airplane and helicopter, as shown.
